DESIGN.

H. C. BASCOM & T. S. HEISTER.

PARLOR STOVE.

No. 15,647.

Patented Dec. 30, 1884.

UNITED STATES PATENT OFFICE.

H. CLAY BASCOM, OF TROY, AND TOBIAS S. HEISTER, OF LANSINGBURG, NEW YORK, ASSIGNEES TO THE YOUNGSTOWN STOVE COMPANY, OF YOUNGSTOWN, OHIO.

DESIGN FOR A PARLOR-STOVE.

SPECIFICATION forming part of Design No. 15,647, dated December 30, 1884.

Application filed October 13, 1884. Term of patent 7 years.

To all whom it may concern:

Be it known that we, H. CLAY BASCOM, a citizen of the United States, residing in the city of Troy, in the county of Rensselaer and State of New York, and TOBIAS S. HEISTER, a citizen of the United States, residing in the village of Lansingburg, in said county and State, have jointly invented and produced a new and original Design for Parlor-Stoves, of which the following is a specification, reference being had to the accompanying engraving of a stove having said design.

This design relates to several new and distinctive ornamental figures and forms and combinations thereof, which go to make up the whole design, as hereinafter specified.

One part of this design embraces the shape and ornamentation of the cover A, the same being of oblong quadrilateral form, and consisting of the flat top a, lower border, b, and the convexly-curved open-work portion c, having the series of compound arches c' rising from the row of semi-rosettes c'', and the intermediate downwardly-tapering arch-supports, c'''.

Another distinctive part of this design is the shape and ornamentation of the corner pilasters, each being of flat rectangular form, and consisting of the capital B, having the panel d, with the compound stem and leaf ornament d', the columnar part D, having the panel f, with leaves f' at top and bottom, and the intermediate compound leaf, scroll, and rosette ornament, g, and the pedestal E, having the panel h, and the leaf and floral ornament z.

Another integral part of this design is the shape and ornamentation of the projecting front portion, consisting of the fire-box casing I, having the row of pillars n, with rosettes n' at the top, and intermediate ornamentalations o o', the hood G, having the curved and ornamented upper corner part, k, the flat arch l, and the upright end, with the mica lights l', and the name-plate F, having the ornamental parts j j' j'', all substantially as shown. Another part is the shape and ornamentation of the illuminating-doors H, the same being of rectangular panel form, and each having

the central rosette, m, semi-rosettes m' at top and bottom, and the intervening curved and angular bar-like open-work m'', as shown.

Another part of this design is the shape and ornamentation of the forward base-extension, consisting of the hearth-plate R, the base-plate S, and the intermediate upright portion embracing the front plate, J, having the rectangular corner parts, p, and intervening rectangular panel with leaf ornaments p', rectangular apertures p'', and rosette ornaments p''', and the paneled end plate, K, having the leaf ornaments q and rosette ornaments q', as shown. Another part is the ornamentation of the end of the stove, consisting of the leaf ornaments r, picket ornamentations r', and rosettes r'' on the lower portion, L, the compound ornaments s, panel s', and ornaments s'' on the portion M, and the top and bottom ornaments, t t', and intermediate ornamentations, u u', on the panel portion N, as shown.

Another integral part of this design is the shape and ornamentation of the legs P, embracing the upper swelling and laterally-extending portion, having the corner rosettes, x, the central rosette, x', and leaf ornaments y, with the contracted ornamental portion z. This design for the legs is distinct from that of the skirtings O, which are shown added to the legs, and embrace the downwardly-extending rosette r, lateral rosettes r', straight bottom edging, r'', and the laterally-extending scroll, vine, and leaflet ornaments w.

The whole design embraces the shape and ornamentation of the cover A, top Q, corner pilasters consisting of the parts B D E, tile-holding parts e, having bars e e', front projecting portion, I G F, doors H, base-extension R S J K, end portion L M N, legs P, and skirtings O, substantially as shown in the accompanying engraving.

We claim as new—

1. In a design for a stove, the shape and ornamentation of the cover A, embracing the parts a b c c' c'', as set forth.
2. In a design for a stove, the shape and ornamentation of the corner pilasters, each consisting of the capital B, having the parts d d',

(over)

the columnar portion D, having the parts $f f'$ g , and the pedestals E, having the parts $h i$, substantially as shown and described.

3. In a design for a stove, the shape and ornamentation of the front projecting portion consisting of the fire-box casing I, having the ornamental parts $n n' o o'$, the hood G, having the parts $k l l'$, and the ornamental plate F, having the parts $j j' j''$, as shown and described.

4. In a design for a stove, the shape and ornamentation of the illumination doors H, embracing the parts $m m' m''$, as set forth.

5. In a design for a stove, the shape and ornamentation of the base-extension, consisting of the parts RS J $p p' p'' p'''$ and K $q q'$, as shown and described.

6. In a design for a stove, the ornamentation of the end L M N, consisting of the ornamental parts $r r' r''$, $s s' s''$, and $t t' u u'$, as shown and described.

7. In a design for a stove, the shape and ornamentation of the legs P, consisting of the parts $x x' y z$, as shown and described.

8. In a design for a stove, the shape and ornamentation of the base-support, consisting of the legs P, having the parts $x x' y z$, and the intermediate skirtings, O, having the parts $v v' v'' w$, as shown and described.

9. The design for a stove, embracing the parts A B C D E F G H I J K L M N O P Q R S, shaped and ornamented substantially as shown.

In testimony whereof we hereunto set our hands, in the presence of two subscribing witnesses, this 10th day of October, 1884.

H. CLAY BASCOM.
TOBIAS S. HEISTER.
